UNITED STATES PATENT OFFICE.

HAMILTON T. HOWELL, OF NEW YORK, N. Y., ASSIGNOR TO ALFRED VESTER SONS, INC., OF PROVIDENCE, RHODE ISLAND, A CORPORATION OF RHODE ISLAND.

DESIGN FOR A DEEP-BODY SHELL.

60,029.

Specification for Design.

Patented Dec. 20, 1921.

Application filed March 30, 1921. Serial No. 457,074. Term of patent 14 years.

To all whom it may concern:

Be it known that I, HAMILTON T. HOWELL, a citizen of the United States, and residing at New York, in the county of New York and State of New York, have invented a certain new, original, and ornamental Design for a Deep-Body Shell, of which the following is a specification, reference being had to the accompanying drawing, forming part thereof.

Figure 1 is a front view of a deep body shell, one-half of the surface ornamentation being shown.

Fig. 2 is a bottom plan view of the same.

I claim:

The ornamental design for a deep body shell, as shown.

HAMILTON T. HOWELL.
